UNITED STATES PATENT OFFICE

172,571

COMBINED BOTTLE CAP AND BOTTLE OPENER

Willis O. C. Ward, Westlake, Ohio

Application November 12, 1953, Serial No. 27,574

Term of patent 14 years

(Cl. D58—26)

To all whom it may concern:

Be it known that I, Willis O. C. Ward, a citizen of the United States and a resident of Westlake, in the county of Cuyahoga and State of Ohio, having invented a new, original, and ornamental Design for a Combined Bottle Cap and Bottle Opener, of which the following is a specification, reference being had to the accompanying drawing, forming a part hereof.

In said drawing, Fig. 1 is a top perspective view of a combined bottle cap and bottle opener showing my new design; and,

Fig. 2 is a bottom perspective view thereof.

I claim:

The ornamental design for a combined bottle cap and bottle opener, as shown.
